UNITED STATES PATENT OFFICE

JOSEPH C. HAKIM, OF HOBOKEN, NEW JERSEY

MEANS FOR PRODUCING MULTICOLOR PRINTING ROLLS

Application filed March 29, 1930. Serial No. 440,013.

This invention relates to the art of printing by means of engraved rollers, such rollers being suitable for use in printing multi-color designs and also for embossing and watermarking paper.

While the invention is capable of general use, it is particularly directed to the successive or repeated printing at regular intervals and in multicolor, of a design on elongated 10 sheets of material such as textile fabrics, wall paper or the like, and in this connection it is an object of the invention to provide a novel means for engraving the printing rollers to assure that each successive reproduction of 15 the complete design will be an exact duplicate of the preceding reproduction thereof.

With the foregoing and other objects in view, the invention consists in the novel features of construction, combination and arrangement of parts, as will be hereinafter 20 more fully described, illustrated in the accompanying drawing and defined in the appended claim.

In the drawing, wherein like characters of 25 reference denote corresponding parts in the different views:—

Figure 1 is a side elevation of a mechanism constructed in accordance with the invention.

Figure 2 is a top plan view of said mechanism; and

Figure 3 is a transverse sectional view through said mechanism on the line 3—3 of Fig. 1.

According to the present invention, a number of photographic negatives are made of 35 the complete design that is to be reproduced, one negative for each different color that is to be employed in printing the design. These negatives then are treated in any suitable 40 manner so that only that portion of the design that is to be reproduced in a given color remains on the respective negatives. That is to say, assuming that a given design is to be reproduced in three colors—red, yellow and 45 green, for example—three negatives of the complete design are made and from one of these negatives all portions of the design are suitably deleted except those portions that are to appear in red; from a second of the 50 negatives, all portions of the design except

those portions that are to appear in yellow are deleted, and from the third negative all portions of the design are deleted except those portions that are to appear in green. The negatives of the different portions of 55 the design then are photographically reproduced on flat lithographic plates, respectively, in any suitable or desired manner, all of the foregoing being old in the art and the present invention beginning with the production of the lithographic plates. 60

In other words, the present invention resides essentially in effecting a transfer of ink from each lithographic plate directly to a printing roller by rolling the latter under 65 pressure over the plate and thereafter treating the roller in an acid bath in known manner to effect etching of the roller surface surrounding the portion of the design appearing thereon in ink, thereby to produce what 70 is known as an engraved roller suitable to receive ink for printing purposes.

If the design that is to be printed is not intended to be continuous, but is to be printed at spaced intervals it is not essential that the circumference of the rollers correspond to the width of the design. It is, however, a feature of the present invention to make the circumference of the rollers correspond exactly to one another and to the width of the 75 design in instances where a design is to be printed continuously on an elongated sheet, thus to insure exact register of the different portions of the complete design printed from 80 said rollers, assuring of course proper adjustment of the rollers with respect to one another when placed in the printing machine. 85

Referring now to the mechanism illustrated in the accompanying drawing for effecting transfer of a design from a lithographic plate to a printing roller, in accordance with this invention, A designates generally a supporting frame on which is mounted a bed plate 10 and which supports, at each side of said bed plate, a trackway 11 and a rack 12 provided, respectively, in any suitable or desired manner.

A carriage B of substantially inverted U-shape is provided with rollers 13 which co-operate with the trackways 11 whereby said 100

carriage is mounted on the frame A for travel over the bed plate 10, and to effect such travel of said carriage same is provided with a shaft 14 equipped with pinions 15 disposed in mesh with the teeth of the racks 12, and a suitable handle 16 is provided for rotating said shaft.

5 The carriage B carries a printing roller supporting frame designated generally as C which is vertically adjustable relative to said carriage. That is to say, the carriage B is inclusive at each side thereof bracket arms 17 in which rack bars 18 are mounted for vertical sliding adjustment, said rack bars having brackets 19 in which are adapted to be secured bearing blocks 20 to receive the usual projecting shaft elements at the ends of the printing roller designated as 21, whereby said roller is adapted to be supported for rotation by the carriage B.

10 20 For effecting vertical adjustments of the roller carrying rack bars 18, a shaft 22 is suitably journaled in the carriage B and on said shaft are secured pinions 23 disposed in mesh with the teeth of said rack bars, any suitable 15 means such as a handle 24 on said shaft being provided for rotating same.

15 30 In the use of the foregoing mechanism, an inked lithographic plate designated as 25 is placed upon the bed plate 10 and a printing roller 21 is mounted on the carriage B in the manner stated. By means of the handle 16 the carriage B then is moved to cause the roller 21 to roll over said lithographic plate, and by means of the handle 24 the frame C is 35 depressed to cause the roller to bear with a desired pressure against said plate during its travel over the same. Thus, a transfer of ink from the plate 25 to said roller 21 is effected, and by then removing the roller 21 and etching 40 same in a known manner to cause the design appearing in ink thereon to stand out in relief, an exact reproduction on the roller of the design on the lithographic plate is obtained, the roller thereby being rendered suitable for printing purposes.

45 50 When the design on one of the plates 25 has been transferred to one of the rollers 21, a second lithographic plate is placed on the bed plate 10 in lieu of the first lithographic plate and another roller is mounted on the carriage B. The design transfer operation described in connection with the first plate 25 and roller 21 then is repeated to effect a reproduction of the design on the second plate 55 onto the second roller, and this operation is repeated for each of the other lithographic plates and rollers, after which the several rollers are assembled in a printing machine and properly adjusted so that each successive 60 roller will fill in a vacant portion of the design on a sheet as the latter is moved past the respective rollers, the design being completed when the last roller has been passed.

65 68 By providing rollers 21 of a circumference corresponding exactly to the width of the de-

sign, and by transferring the design portions of the respective lithographic plates directly to the respective rollers, exact registration of the different portions of the design printed from said rollers and a perfect continuous 70 reproduction of the complete design is assured, and this is especially true due to the holding of the rollers against the lithographic plates under considerable pressure during 75 rolling of said rollers over said plates, whereby a sharp outline of each plate design is caused to be reproduced on its related roller.

If desired, any suitable means may be employed to assure that each successive lithographic plate shall be disposed on the bed plate 10 in exactly the same position as its predecessor, and that each successive roller shall be disposed on the carriage B in exactly the same position as its predecessor, but this is not essential inasmuch as the rollers ordinarily are adjustable in the printing machine to effect registration of the different portions of the design printed from the respective 85 rollers.

Without further description it is thought 90 that the features and advantages of the invention will be readily apparent to those skilled in the art, and it will of course be understood that changes in the form, proportion and minor details of construction may be 95 resorted to, without departing from the spirit of the invention and scope of the appended claim.

I claim:

100 Mechanism for use in effecting transfer of a design from a lithographic plate to a printing roller comprising a bed structure on which the lithographic plate is adapted to be supported, a carriage mounted on said bed structure for movement with respect thereto over a lithographic plate supported thereon, and means for mounting a printing roller on said carriage for vertical adjustment with respect thereto whereby the pressure of the roller against the lithographic plate during movement of the carriage over the bed structure may be variably predetermined, said means comprising a pair of rack bars mounted on the carriage for vertical adjustments, 105 means for vertically adjusting said rack bars, and brackets carried by said rack bars, respectively, for the reception of bearing blocks for the printing roller, each bracket being open at one side to facilitate the insertion and removal of the bearing blocks thereby to facilitate the changing of the printing rollers.

110 In testimony whereof I hereunto affix my signature.

JOSEPH C. HAKIM.
